(57) **CLAIM**

I claim the ornamental design for a pastry cover, as shown and described.

DESCRIPTION

FIG. 1 is a top front perspective view of a pastry cover showing my new design.

FIG. 2 is a front view thereof.

FIG. 3 is a rear view thereof.

FIG. 4 is a side view thereof.

FIG. 5 is a top view thereof; and,

FIG. 6 is a bottom view thereof.

The broken lines in FIGS. 1-6 represent environment that form no part of the claimed design.

1 Claim, 6 Drawing Sheets
